UNITED STATES PATENT OFFICE

2,516,490

TRAVERSE CRANE

Frederick W. Steinmeyer, Oakland, Calif.

Application December 5, 1944, Serial No. 566,757

4 Claims. (Cl. 160—333)

1

The present invention relates to improvements in a traverse crane, and it consists of the combinations, constructions and arrangements herein-after described and claimed.

An object of my invention is to provide a traverse crane that is slidably mounted on a window frame, the crane supporting a curtain or drapes and being movable laterally for exposing any portion of the window desired. This permits the drapes or curtains to be moved away from a position in front of the window so as to permit the entrance of sunlight into the room or it will permit a person to have an unobstructed view through the window. I am aware of curtains and drapes which may be moved along a stationary supporting rod, but my invention contemplates the moving of the traverse crane with the curtain or drape as a unit.

A further object of my invention is to provide a device of the type described in which pull cords may be used for moving the two traverse cranes into the proper position with respect to the window. The crane may be supported at any desired position so that a small portion or the entire window may be uncovered. The device is simple in construction and durable and efficient for the purpose intended.

Other objects and advantages will appear in the following specification, and the novel features of the device will be particularly pointed out in the appended claims.

My invention is illustrated in the accompanying drawing forming a part of this application, in which:

Figure 1 is a horizontal section through a window frame showing my device operatively applied thereto;

Figure 2 is a front elevation of the window showing one of the traverse cranes in position;

Figure 3 is a front elevation of the traverse crane and illustrates the manner of support;

Figure 4 is a transverse section taken along the line 4—4 of Figure 1;

Figure 5 is a view similar to Figure 1 but shows a modified form of the traverse crane;

Figure 6 is a front elevation of one of the traverse cranes shown in Figure 5;

Figure 7 is a top plan view of the traverse crane shown in Figure 5;

Figure 8 is a transverse section taken along the line 8—8 of Figure 7; and

Figure 9 is an end view of Figure 7 but looking in the direction of the arrows 9—9.

While I have shown only the preferred forms of my invention, it should be understood that

2

various changes or modifications may be made within the scope of the appended claims without departing from the spirit and scope of the invention.

5 In carrying out my invention I make use of a window indicated diagrammatically at A in Figure 1. Brackets B and B' are placed at the sides of the window. The brackets are U-shaped, see Figures 1 and 3, and are secured to the wall or window frame by screws 4 or other suitable fastening means. I do not wish to be confined to the particular size or shape of the bracket. Each bracket carries a plurality of idler supporting wheels 2. I have shown two of the wheels mounted above a traverse crane C and one wheel mounted below the crane. Figure 1 shows the wheels 2 as having rims 3 that overlie the top and bottom edges 4 of the traverse crane. In this way the traverse crane is held in a horizontal position but may be moved in the direction of its length as indicated by the broken lines in Figure 3.

20 Each traverse crane C has a web or flange 5 projecting outwardly from the outer face of the base portion. The crane is L-shaped and the web has openings 6 therein for receiving supporting eyes 7 that carry a drape 8. The drape 8 is gathered into loops 9 to form a pleasing appearance. The bracket and crane are strong enough to support the drape. There are two traverse cranes C for each window and they may be moved with respect to their supporting rollers or wheels 2 and will remain in adjusted position. The adjustment may be made by hand if desired or pull cords may be used.

25 30 35 40 45 50 In Figures 1 and 2 I show the traverse cranes C provided with lugs 10 to which pull cords 11 are attached. Each cord is passed over a pulley wheel 12 which in turn, is rotatably carried by the bracket B or B'. The free end of each pull cord is provided with a ring 13. A second pull cord 14 is attached to the L-shaped portion of each crane and is passed over a second idler pulley 15. The free end of each cord 14 has a ring 16. A pulling of the rings 13 will move the traverse cranes so as to carry the drapes 8 away from a position in front of the window. A return movement of the cranes and drapes is effected by pulling the rings 16. Figure 4 shows the bracket B' and illustrates how the wheels 2 with their rims 3 engage with the base of the traverse crane C. The flange 5 extends between the rims 3 of the upper and lower wheels and if desired the rims may ride on the faces of the flange.

In Figures 5 to 9 inclusive I show a slightly modified form of the invention. Here the window

is indicated generally at D and the traverse cranes E are carried by wheels 17 that are similar to the wheels 2. Figure 7 shows the crane E provided with means for supporting a curtain rod 18. This means may include eye pieces 19 and 20 placed at the ends of the crane E and shown in detail in Figure 9. A hook 21 extends from the bend in the crane E and is designed to underlie the bend in the curtain rod 18.

A curtain 22 hangs from the rod 18. If desired, an ornamental piece 23 may hang in front of the curtain and adjacent to the top. This ornamental piece may be supported by hooks 24, see Figure 8, that are placed over the curtain rod 18. The ornament 23 may take the shape desired, as for example, the shape shown in Figure 6.

The operation of this form of the device is identical to that of the form shown in Figures 1 to 4 inclusive. The wheels 17 are supported by brackets E which are similar to the brackets B and B' and are secured to the window frame. Draw cords 25 and 26 are passed over pulleys 27 and 28 and may be actuated for moving the cranes E from a position in front of the window to a position alongside of the window or any other position intermediate these two extreme positions. If desired the curtains 22 may be held back by a loop 29 to expose a lower portion of the window, see Figure 6. If one not wish to be confined to the particular type of curtain rod supporting means which comprises the eye pieces 19 and 20 and the hook 21.

I claim:

1. In a device of the type described; a bracket 35 securable to a window frame; a traverse crane, flanged wheels rotatably mounted on the bracket, two wheels contacting with the upper edge of the crane and one wheel with the lower edges for slidably securing the crane to the bracket and supporting the crane in a horizontal position; and a curtain rod carried by the crane and movable in a horizontal plane therewith as a unit, said rod having its ends connected to the crane by eye pieces and the portion of the rod disposed between its ends being supported by a hook.
2. In a device of the type described; a laterally adjustable crane, T-shaped in cross section; means for slidably supporting the crane adjacent to a window with the web of the T lying in a

horizontal plane and being contacted by the supporting means; and a window covering material carried by the web at a point where it is clear of the crane-supporting means; whereby the crane and window covering material can be freely adjusted laterally as a unit to cover a desired portion of the window or expose the window.

3. In a device of the type described, a laterally adjustable crane, T-shaped in cross section; means for slidably supporting the crane adjacent to a window, the crane having a web portion paralleling the plane of the window and being spaced therefrom and slidably supported by the crane supporting means, one end of the crane being curved toward the wall surrounding the window, and a window covering material carried by the crane and extending around the curved portion of the crane supporting means; whereby the crane and window covering material can be freely adjusted laterally as a unit to cover a desired portion of the window or expose the window.

4. In a device of the type described; a laterally adjustable crane, T-shaped in cross section; means for slidably supporting the web portion of the crane adjacent to a window; a window covering material carried by the web portion of the crane at a point clear of the crane supporting means; a cord-supporting member; and a pull cord attached to each end of the crane and passing over and depending from said member for moving the crane in the desired direction when the proper cord is pulled.

FREDERICK W. STEINMEYER.
